AQUARIUM STAND

Richard S. Young, Frankenmuth, and Leo E. Hearn, Flint, Mich., assignors to Pentaco Enterprises Corporation, Chesaning, Mich.

Filed June 12, 1972, Ser. No. 261,905

Term of patent 14 years

Int. Cl. D30—02; D06—03
U.S. Cl. D30—12

FIG.2

FIG. 1 is a perspective view of an aquarium stand, showing our new design;

FIG. 2 is an end elevational view, the opposite end being substantially a mirror image thereof;

FIG. 3 is a top plan view;

FIG. 4 is a bottom plan view; and

FIG. 5 is a side elevational view, the opposite side being substantially a mirror image thereof.

We claim:

The ornamental design for an aquarium stand, substantially as shown and described.
